UNITED STATES PATENT OFFICE.

CARL N. QUIMBY, OF ARLINGTON, MASSACHUSETTS.

DESIGN FOR A NOSE-GUARD FOR EYEGLASS-MOUNTING.

44,322.

Specification for Design.

Patented July 8, 1913.

Application filed August 16, 1912. Serial No. 715,527. Term of patent 14 years.

To all whom it may concern:

Be it known that I, CARL N. QUIMBY, a citizen of the United States, residing at the city of Arlington, county of Middlesex, State of Massachusetts, have invented a new, original, and ornamental Design for Nose-Guard for Eyeglass-Mounting, of which the following is a specification, reference being had to the accompanying drawing, forming part thereof.

I claim:

The ornamental design for a nose guard for eye-glass mounting as shown.

CARL N. QUIMBY.

Witnesses:

MARGARET A. McCANN,
FRANCES J. FALVEY.
